(57) **CLAIM**

The ornamental design for a mitering chop saw, as shown and described.

DESCRIPTION

FIG. 1 is a front view of a mitering chop saw embodying the new design;

FIG. 2 is a back view thereof;

FIG. 3 is a right side view thereof;

FIG. 4 is a left side view thereof;

FIG. 5 is a top view thereof;

FIG. 6 is a bottom view thereof; and,

FIGS. 7-10 are each a perspective view thereof.

The broken lines shown in the drawings show portions of the mitering chop saw that form no part of the claimed design.
